(57) **CLAIM**

The ornamental design for a transfer case gear housing, as shown and described.

DESCRIPTION

FIG. 1 is a perspective, environmental view of one embodiment of our transfer case gear housing;

FIG. 2 is a perspective view of our transfer case gear housing;

FIG. 3 is a front view of the transfer case gear housing of FIG. 2;

FIG. 4 is a rear view of the transfer case gear housing of FIG. 2;

FIG. 5 is a right side view of the transfer case gear housing of FIG. 2;

FIG. 6 is a left side view of the transfer case gear housing of FIG. 2;

FIG. 7 is a top plan view of the transfer case gear housing of FIG. 2;

FIG. 8 is a bottom plan view of the transfer case gear housing of FIG. 2;

FIG. 9 is a perspective, environmental view of another embodiment of our transfer case gear housing;

FIG. 10 is a perspective view of the transfer case gear housing of FIG. 9;

FIG. 11 is a perspective view of the transfer case gear housing of FIG. 10;

FIG. 12 is a rear view of the transfer case gear housing of FIG. 10;

FIG. 13 is a right side view of the transfer case gear housing of FIG. 10;

FIG. 14 is a left side view of the transfer case gear housing of FIG. 10;

FIG. 15 is a top plan view of the transfer case gear housing of FIG. 10; and,

FIG. 16 is a bottom plan view of the transfer case gear housing of FIG. 10.

The broken line showing in the drawings is included for the purpose of illustrating environment and forms no part of the claimed design for our transfer case gear housing.
